UNITED STATES PATENT OFFICE.

EVERETT L. THOMPSON, OF DOVER, NEW JERSEY, AND CHARLES W. TRIBKEN, OF BROOKLYN, NEW YORK, ASSIGNEES TO SYPHO-CHEMICAL SPRINKLER CORPORATION, OF CROTON-ON-HUDSON, NEW YORK, A CORPORATION OF NEW YORK.

CHEMICAL FIRE-EXTINGUISHING APPARATUS.

1,285,468.

Specification of Letters Patent. Patented Nov. 19, 1918.

Application filed July 26, 1915. Serial No. 41,836.

To all whom it may concern:

Be it known that we, EVERETT L. THOMPSON, of Dover, Morris county, New Jersey, and CHARLES W. TRIBKEN, of borough of Brooklyn, Kings county, city and State of New York, citizens of the United States, have made a certain new and useful Invention Relating to Chemical Fire-Extinguishing Apparatus, of which the following is a specification, taken in connection with the accompanying drawing, which forms part of the same.

This invention relates especially to automatic fire extinguishing apparatus in which under fire emergency conditions supplemental extinguishing liquid is applied to the distributing system as by the emergency action of a chemical supply tank so as to be discharged at the desired high pressure from the operating distributing device. The chemical mixing devices coöperating with this chemical tank may be brought into emergency action by the suction created in the substantially closed upper part of the distributing system by the commencement of flow from the opened distributing device, this suction impulse acting through a suitable pneumatic suction connection or actuating pipe which is protected against injury by being inclosed in a liquid filled casing, such as a suction protector pipe which may form part of the distributing system or be connected therewith.

In the accompanying drawings showing in a somewhat diagrammatic way illustrative embodiments of the invention—

Figure 1 is an elevation partly in section of one form of the invention; and

Fig. 2 is a similar view showing a modified arrangement.

As shown in a somewhat diagrammatic way in Fig. 1 the distributing system may comprise a series of distributing lines 2, 3, 4, provided with suitable distributing devices such as the automatic sprinkler heads 11 and connected through the riser or supply pipe 1, for instance, with any suitable supply of extinguishing liquid, such for example as the chemical tank 26 containing carbonate extinguishing liquid 27 so that under emergency conditions the chemically developed pressure forces this liquid up through the strainer 28 at the lower end of this supply connection or pipe 1 and past

the check valve 41 into the distributing system so as to fill all parts thereof, including suitable cross connections, such as 5, 6, which may be arranged at suitable points. The distributing system may be normally charged with any suitable extinguishing liquid, such as, for example, as a non-freezing solution for low temperature work, the entire distributing system being preferably filled so as to secure the more rapid discharge from any distributing device which comes into action. A suitable priming actuating tank, such as 12, may be connected in any desired or convenient way to the distributing system so as to supply thereto extinguishing liquid under suitable pressure at the commencement of flow from any of the distributing devices. This priming tank may, if desired, be provided with the gage glass 14 to observe the extent to which the liquid fills the tank and a venting aperture 13 preferably of pin-hole size may also be provided at the upper end of this tank to take care of slight temperature expansion.

Under emergency conditions the liquid which flows from the priming actuating tank creates a pressure reduction or suction in the upper part of the tank and connected distributing system which is nearly or substantially closed under these conditions so that this suction impulse is available for actuating any desired emergency device which may be utilized for the supply of supplemental extinguishing liquid to the distributing system. For this purpose a pneumatic suction connection or actuating pipe 15 may extend from the upper end of the system, such as the upper part of the actuating tank, for instance, to any suitable emergency device, such as the starting siphon 20, the upper part of which may be connected with the end 43 of the suction pipe and which may have one leg 22 dipping into the sulfuric or other acid 29 in the acid chamber 18 while its other or discharge leg 25 may communicate with the chemical tank 26 and may, for example, extend within the priming cup or container 24 containing a suitable quantity of similar acid or liquid neutral thereto, so that when the suction impulse takes place the acid quickly fills the siphon sufficiently to cause its emergency operation and discharge the acid into the carbonate liquor 27 in the chemical tank, the

flow of the acid continuing because the unimpeded flow of air can take place in the opposite direction through the equalizing pipe 39. Since the suction pipe is such a 5 vital part of the system it is desirable to protect it against accidental injury or displacement and for this purpose it is desirable to arrange the suction pipe within a suitable liquid casing such as one of the 10 liquid filled pipes forming part of the distributing system or connected therewith. This suction pipe may therefore be inclosed in the suction protector pipe 10 extending around this suction pipe throughout substantially its entire extent so as to make it 15 practically impossible for its accidental injury to occur without at once calling attention to such a condition through escape of liquid. As shown in Fig. 1 a special suction 20 protector pipe may be used for this purpose extending downward from the priming actuating tank 12 to the emergency device or chemical mixing means and if desired a suitable packing and stuffing box 42 may be 25 used around the end of the suction pipe to prevent the liquid from the protector casing escaping into the acid chamber, for instance. Under these conditions it is desirable for 30 some purposes to have one or more reduced actuating connections, such as 7, between the distributing system and the actuating tank or this suction protector pipe connected thereto which serves to supply the initial flow 35 of extinguishing liquid to the system under emergency conditions. By properly proportioning the size of such an actuating connection the rate of flow under fire conditions can be so arranged as to secure the emergency actuation of the chemical mixing 40 means or other emergency devices after the desired time interval. For example, the connection 7 may with advantage be made somewhat smaller than the connection 9 coöperating with the upper part of the distributing system and suitable difference in 45 effective area which may be inversely proportional to the effective head on the connected distributing devices may be made where these actuating connections lead to 50 more or less separated distributing lines or devices. It is also desirable to provide a suitable drain device, such as the drain valve 17 in the lower part of the suction protector pipe 10 so that any remaining liquid may 55 be withdrawn therefrom after the emergency action of the apparatus has occurred, for example.

It is not, however, necessary to have a 60 separate suction protector pipe in all cases since in many installations the protector pipe may as shown in Fig. 2 also constitute the main riser or supply pipe 1 leading directly from the chemical tank 26 and the 65 pneumatic suction pipe 15 may extend from the actuating tank down inside the upper

end of this supply pipe or riser and may then extend within a separate protector pipe and connection 30, 31 to the starting siphon or emergency device 20. In this instance the emergency operation of the system is 70 brought about in substantially the same way as soon as one of the distributing devices 11 on one of the distributing lines 32 for instance, comes into emergency operation.

This invention has been described in connection with a number of illustrative embodiments, forms, proportions, materials, arrangements and numbers of parts, to the details of which disclosure the invention is 75 not of course to be limited, since what is 80 claimed as new and what is desired to be secured by Letters Patent is set forth in the appended claims.

1. In chemical fire extinguishing apparatus, a distributing system normally charged 85 with non-freezing extinguishing liquid and comprising distributing lines and connected automatic distributing devices, a supplemental supply of extinguishing liquid comprising a chemical pressure tank and co-operating chemical mixing devices, a valved 90 supply pipe connection between said tank and said distributing system, a priming actuating tank charged with liquid adapted to be connected to said distributing system 95 to supply liquid to the system on the beginning of flow from the distributing devices, a pneumatic suction pipe extending adjacent the top of said actuating tank and connected to said chemical mixing devices to 100 effect their emergency operation, a liquid filled suction protector pipe inclosing said suction actuating pipe, between said actuating tank and said chemical mixing means and serving to connect said actuating tank 105 to said system and a drain device adjacent the bottom of said protector pipe.

2. In chemical fire extinguishing apparatus, a distributing system normally charged 110 with extinguishing liquid and comprising distributing lines and connected distributing devices, a supplemental supply of extinguishing liquid comprising a chemical pressure tank and co-operating chemical mixing devices, a supply pipe connection between 115 said tank and said distributing system, a priming actuating tank charged with liquid adapted to be connected to said distributing system through a reduced actuating connection to supply liquid to the 120 system on the beginning of flow from the distributing devices, a pneumatic suction pipe extending adjacent the top of said actuating tank and connected to said chemical mixing devices to effect their emergency 125 operation, and a liquid filled suction protector pipe inclosing said suction actuating pipe between said actuating tank and said chemical mixing means and serving to connect said actuating tank to said system. 130

3. In chemical fire extinguishing apparatus, a distributing system normally charged with extinguishing liquid and comprising distributing lines and connected distributing devices, a supplemental supply of extinguishing liquid comprising a chemical pressure tank and coöperating chemical mixing devices, a supply pipe connection between said tank and said distributing system, a priming actuating tank charged with liquid adapted to be connected to said distributing system through a connection to supply liquid to the system on the beginning of flow from the distributing devices, a pneumatic suction pipe extending adjacent said actuating tank and connected to said chemical mixing devices to effect their emergency operation, and a liquid filled suction protector pipe inclosing said suction actuating pipe between said actuating tank and said system.

4. In chemical fire extinguishing apparatus, a distributing system normally charged with non-freezing extinguishing liquid and comprising distributing lines and connected automatic distributing devices, a supplemental supply of extinguishing liquid comprising a chemical pressure tank and coöperating chemical mixing devices, a valved supply pipe connection between said tank and said distributing system, a priming actuating tank charged with liquid connected to said distributing system through a reduced actuating connection to supply liquid to the system on the beginning of flow from the distributing devices, a pneumatic suction pipe extending adjacent the top of said actuating tank and connected to said chemical mixing devices to effect their emergency operation and a liquid filled suction protector pipe communicating with said system and inclosing said suction actuating pipe between said actuating tank and said chemical mixing means.

5. In chemical fire extinguishing apparatus, a distributing system normally charged with extinguishing liquid and comprising distributing lines and connected distributing devices, a supplemental supply of extinguishing liquid comprising a chemical pressure tank and coöperating chemical mixing devices, a supply pipe connection between said tank and said distributing system, a priming actuating tank charged with liquid connected to said distributing system to supply liquid to the system on the beginning of flow from the distributing devices, a pneumatic suction pipe extending adjacent the top of said actuating tank and connected to said chemical mixing devices to effect their emergency operation and a liquid filled suction protector pipe inclosing said suction actuating pipe between said

actuating tank and said chemical mixing means.

6. In fire extinguishing apparatus, a distributing system normally charged with extinguishing liquid and comprising distributing devices, a supplemental supply of extinguishing liquid comprising a pressure tank connected to said distributing system, a primary actuating tank charged with liquid connected to said distributing system, to supply liquid to the system on the beginning of flow from the distributing devices, a pneumatic suction pipe connected adjacent the top of said system and connected to said pressure tank to effect its emergency operation and a liquid filled suction protector pipe connected to said system and inclosing portions of said suction actuating pipe between said actuating tank and said pressure tank.

7. In fire extinguishing apparatus, a distributing system normally charged with extinguishing liquid and comprising distributing devices, a supplemental supply of extinguishing liquid comprising a pressure tank connected to said distributing system, a pneumatic suction pipe connected adjacent the top of said system and connected to said pressure tank to effect its emergency operation and a liquid filled suction protector pipe inclosing portions of said suction actuating pipe.

8. In chemical fire extinguishing apparatus, a distributing system normally charged with non-freezing extinguishing liquid and comprising separated distributing lines and connected automatic distributing devices, an emergency device including a supplemental supply of extinguishing liquid comprising a chemical pressure tank and coöperating chemical mixing devices, a supply pipe connection between said emergency device and said distributing system, a priming actuating tank charged with liquid adapted to be connected to said distributing system to supply liquid to the system on the beginning of flow from the distributing devices, a pneumatic suction pipe connected adjacent the top of said system and connected to said emergency device to effect its emergency operation, a liquid filled suction protector pipe inclosing said suction actuating pipe between said actuating tank and said emergency device and serving to connect said priming tank to said system and different sized reduced actuating connections between said protector pipe and the distributing lines on different levels, the effective area of said actuating connections being inversely proportional to the effective head on their distributing devices.

9. In chemical fire extinguishing apparatus, a distributing system normally charged with extinguishing liquid and comprising separated distributing lines and con-

4

nected automatic distributing devices, an emergency device including a supplemental supply of extinguishing liquid, a supply pipe connection between said emergency device and said distributing system, a priming actuating tank charged with liquid adapted to be connected to said distributing system to supply liquid to the system on the beginning of flow from the distributing devices, a pneumatic suction pipe connected adjacent the top of said system and connected to said emergency device to effect its emergency operation, a liquid filled suction protector pipe inclosing said suction actuating pipe between said actuating tank and said emergency device and different sized reduced actuating connections between said actuating tank and the distributing lines on different levels, the effective area of said actuating connections being inversely proportional to effective head on their distributing devices.

10. In chemical fire extinguishing apparatus, a distributing system normally charged with extinguishing liquid and comprising distributing lines and connected automatic distributing devices, an emergency device including a supplemental supply of extinguishing liquid, a priming actuating tank charged with liquid connected to said distributing system to supply liquid to the system on the beginning of flow from the distributing devices, an emergency actuating pipe connected adjacent the top of said system and connected to said emergency device to effect its emergency operation and a liquid filled suction protector pipe inclosing at least the greater portions of said actuating pipe.

15. In chemical fire extinguishing apparatus, a distributing system normally charged with extinguishing liquid and comprising distributing lines and connected automatic distributing devices, an emergency device, a priming actuating tank charged with liquid adapted to be connected to said distributing system to supply liquid to the system on the beginning of flow from the distributing devices, a suction pipe connected adjacent the top of said system and connected to said emergency device to effect its emergency operation, a liquid filled suction protector pipe inclosing said suction actuating pipe and different sized reduced actuating connections between said actuating tank and the distributing lines on different levels.

20. In chemical fire extinguishing apparatus, a distributing system normally charged with extinguishing liquid and comprising separated distributing lines and connected automatic distributing devices, an emergency device, a priming actuating tank charged with liquid connected to said distributing system to supply liquid to the system on the beginning of flow from the distributing devices, a suction pipe connected adjacent the top of said system and connected to said emergency device to effect its emergency operation, a liquid filled suction protector pipe inclosing portions of said actuating pipe.

25. In chemical fire extinguishing apparatus, a distributing system normally charged with extinguishing liquid and comprising separated distributing lines and connected automatic distributing devices, an emergency device, a priming actuating tank charged with liquid connected to said distributing system to supply liquid to the system on the beginning of flow from the distributing devices, a suction pipe connected adjacent the top of said system and connected to said emergency device to effect its emergency operation, a liquid filled suction protector pipe inclosing portions of said actuating pipe.

30. In chemical fire extinguishing apparatus, a distributing system normally charged with extinguishing liquid and comprising separated distributing lines and connected automatic distributing devices, an emergency device, a priming actuating tank charged with liquid connected to said distributing system to supply liquid to the system on the beginning of flow from the distributing devices, a suction pipe connected adjacent the top of said system and connected to said emergency device to effect its emergency operation, a liquid filled suction protector pipe inclosing portions of said actuating pipe.

35. In chemical fire extinguishing apparatus, a distributing system normally charged with extinguishing liquid and comprising separated distributing lines and connected automatic distributing devices, an emergency device, a priming actuating tank charged with liquid connected to said distributing system to supply liquid to the system on the beginning of flow from the distributing devices, a suction pipe connected adjacent the top of said system and connected to said emergency device to effect its emergency operation, a liquid filled suction protector pipe inclosing portions of said actuating pipe.

40. 11. In chemical fire extinguishing apparatus, a distributing system normally charged with extinguishing liquid and comprising separated distributing lines and connected automatic distributing devices, an

emergency device, a priming actuating tank 45 charged with liquid adapted to be connected to said distributing system to supply liquid to the system on the beginning of flow from the distributing devices, a suction pipe connected adjacent the top of said system and 50 connected to said emergency device to effect its emergency operation and different sized reduced actuating connections between said actuating tank and the distributing lines on different levels. 55

12. In fire extinguishing apparatus, a distributing system normally charged with extinguishing liquid and comprising distributing lines and connected automatic distributing devices, an emergency device including a supplemental supply of extinguishing liquid, a priming actuating tank charged with liquid connected to said distributing system to supply liquid to the system on the beginning of flow from the distributing devices, an emergency actuating pipe connected adjacent the top of said system and connected to said emergency device to effect its emergency operation and a liquid filled suction protector pipe inclosing at least the greater portions of said actuating pipe.

13. In fire extinguishing apparatus, a distributing system normally charged with extinguishing liquid and comprising distributing lines and connected automatic distributing devices, an emergency device, an emergency actuating pipe connected adjacent the top of said system and connected to said emergency device to effect its emergency operation and a liquid filled suction protector pipe inclosing portions of said actuating pipe.

Correction in Letters Patent No. 1,285,468.

It is hereby certified that in Letters Patent No. 1,285,468, granted November 19, 1918, upon the application of Everett L. Thompson, of Dover, New Jersey, and Charles W. Tribken, of Brooklyn, New York, for an improvement in "Chemical Fire-Extinguishing Apparatus," an error appears in the printed specification requiring correction as follows: Page 4, lines 70 and 80, claims 12 and 13, strike out the word "suction;" and that the said Letters Patent should be read with this correction therein that the same may conform to the record of the case in the Patent Office.

Signed and sealed this 21st day of January, A. D., 1919.

[SEAL.]

F. W. H. CLAY,

Acting Commissioner of Patents.
